UNITED STATES PATENT OFFICE.

FRED E. SMITH AND LE ROY HEFLIN, OF FAIRFAX, OKLAHOMA.

SOUNDER FOR TELEGRAPH-CIRCUITS.

1,268,890.

Specification of Letters Patent. Patented June 11, 1918.

Application filed July 28, 1917. Serial No. 183,332.

To all whom it may concern:

Be it known that we, FRED E. SMITH and LE ROY HEFLIN, citizens of the United States, and residents of Fairfax, in the county of Osage and State of Oklahoma, have invented a new and useful Improvement in Sounders for Telegraph-Circuits, of which the following is a specification.

Our invention relates to improvements in sounders for telegraph circuits and it consists in the combinations, constructions and arrangements herein described and claimed.

An object of our invention is to provide a main line sounder which obviates the necessity of a local circuit.

A further object of our invention is to provide a device which embodies all the features of a loud sounder, while at the same time retaining all the quick adjustment features of the standard relay.

A further object of our invention is to provide a sounder having two sets of coils and two armatures, the coils being connected in series and the armatures being connected so that they work synchronously, the force of one magnet being added to that of the other.

A further object of our invention is to provide a device of the type described having a sounder which can be operated in a vertical position in a resonator the same as the ordinary local battery sounder but which is operated by the current from the main line.

Other objects and advantages will appear in the following specification and the novel features of the invention will be particularly pointed out in the appended claims.

Our invention is illustrated in the accompanying drawings, forming part of this application, in which,

Figure 1 is a plan view of the device,

Fig. 2 is a sectional view on the line 2—2 of Fig. 1,

Fig. 3 is a detail view showing connection between the two armatures,

Fig. 4 is a diagrammatic view of the circuits,

Fig. 5 is a detail view showing a portion of the means for connecting the two armatures.

In carrying out our invention we provide a base 1 upon which is mounted a sounder which we have designated in general at S.

This sounder has the usual coils 2, armature 3 and bar 4. The latter is pivoted at 5 on the yoke 6 and is provided with a downwardly extending screw 7 on its underside and with an adjustable spring 8 on its upper side. At C is a second pair of coils. These 60 coils are slidably mounted on a rod 9 which passes through a support 10 and whose threaded end 11 has a nut 12. A spring 13 bears at one end on the cross bar 14 which joins the core pieces of the coils and at the 65 other end on the support 10. Near the opposite end of the coils they are further supported by a standard 15 which has an adjustable cross plate 16 at its top, there being supporting lugs 17 underneath the coils to 70 permit the movement of the coils when the nut 12 is turned.

The armature for the coils C is shown at 18. It is pivoted on a U-shaped bar 19 secured to the base 1. The armature 18 is 75 connected with the screw 7 by means of a spring 20, and a pull-wire 20^x. The latter is provided at one end with a loop which encircles the screw bolt 7, and at the other end with an eye which is engaged by a hook 18^a 80 secured to the armature 18.

It will be obvious that there will be slight play at the end of the pull wire, since the armatures move in arcs of circles. In order to permit this we loop one end of the pull 85 wire around the screw 7 as described, and attach the other end by means of an eye to the hook 18^a. The spring 20 serves to keep the pull wire taut so that the device has the advantage of a flexible pull wire and at the 90 same time lost motion is obviated since the spring bears at one end on the armature 18 and the other end on the screw bolt 7. This construction insures the instant and synchronous action of both armatures. 95

From the foregoing description of the various parts of the device, the operation thereof may be readily understood.

The coils C are connected with the coils of the sounder S in series. In Fig. 4 the 100 main line circuit is shown at L, the coils being shown in series with this main line circuit. It is obvious that the coils C as well as the coils of the sounder S will be energized and this will cause the movement of 105 both armatures 18 and 3, the connection of the armatures through the medium of the spring 20 and a pull-wire 20^x serving to

make the effect of the two armatures cumulative, thus giving strong throw to the sounding bar 4 and sending forth a sound which is amply sufficient for ordinary purposes.

It will be noted that the sounder coils are in a vertical position while the coils C are in horizontal position with an armature which is pivoted on a horizontal axis. The 10 device as described has this feature over the ordinary sounder, that is to say, that in unfavorable weather, when there is a tendency for the armature to stick, the mere adjustment of the horizontal coils by means of 15 the nut 12 is sufficient to overcome this tendency, thus obviating any necessity whatever of adjusting the armature 3.

We further call attention to the fact that in the present instance we have shown two 20 pairs of coils bearing wire with the resistance of two hundred ohms. This construction enables the cores of the coils to reach their maximum strength to demagnetize more quickly. In view of the fact that the 25 two magnets are thus working in synchronism, a stronger and quicker action is obtained than in an ordinary main line sounder with one set of coils.

We claim:—

30 1. The combination of a telegraph sounder having actuating coils and a sounder bar, an auxiliary magnet having an individual movable armature, and means for connecting said movable armature with the sounder bar of the sounder to aid the latter in its movement.

40 2. The combination of a telegraph sounder having actuating coils and a sounder bar, an auxiliary magnet having an individual movable armature, means for connecting said movable armature with the sounder bar of the sounder to aid the latter in its movement, and means for adjusting the position of the coil of the auxiliary magnet with respect to its armature.

45 3. The combination of a telegraph sounder having actuating coils and a sounder bar, an auxiliary magnet having an individual movable armature, a pull wire having flexible connection with the armature of the auxiliary magnet and being connected to the sounder, and a spring for keeping the flexi-

ble pull wire taut at all times to prevent lost motion.

4. The combination of a telegraph sounder 55 having actuating coils and a sounder bar, an auxiliary magnet having an individual movable armature, a pull wire having flexible connection with the armature of the auxiliary magnet and being connected to the 60 sounder, a spring for keeping the flexible pull wire taut at all times to prevent lost motion, and means for adjusting the coil of the auxiliary magnet toward and away from its armature.

5. The combination of a telegraph sounder having actuating coils and a sounder bar, an auxiliary magnet having a movable armature, means for connecting said movable armature with the sounder bar of the sounder 70 to aid the latter in its movement, and means for moving the coils of the auxiliary magnet toward and away from its armature.

6. In combination with a sounder having coils, an armature for the sounder, a sounding bar connected to said armature and being provided with an arm, an auxiliary magnet having a pivoted armature, a pull-wire and spring connecting the armature of the auxiliary magnet with the arm of the sounder 80 bar and means for adjusting the coil of the auxiliary magnet toward and away from its armature.

7. In combination with a sounder having coils, an armature for the sounder, a sounding bar connected to said armature and being provided with an arm, an auxiliary magnet having a pivoted armature, a pull-wire and spring connecting the armature of the auxiliary magnet with the arm, the 90 sounder bar and means for adjusting the coil of the auxiliary magnet toward and away from its armature, said means comprising a slidable bar for supporting the coil of the auxiliary magnet, a standard for supporting the slidable bar, a spring disposed between the coil and the standard and a nut on the end of the slidable bar for adjusting the position of the bar.
